UNITED STATES PATENT OFFICE.

ADOLF HINTENACH, OF NEWARK, NEW JERSEY.

LEATHER ROLLING, GLAZING, OR BRUSHING MACHINE.

Application filed October 5, 1922. Serial No. 592,461.

To all whom it may concern:

Be it known that I, ADOLF HINTENACH, a citizen of the United States, and a resident of Newark, in the county of Essex and State of New Jersey, have invented certain new and useful Improvements in Leather Rolling, Glazing, or Brushing Machines, of which the following is a specification.

This invention relates in general to a mechanical movement for causing a member mounted to oscillate on an axis to travel in a substantially straight path. More particularly the invention relates to a mechanical movement for actuation of a roller, glazing tool or brush in leather rolling, glazing or brushing machines of the type including a yielding table to support the leather to be operated and mechanism swinging about an axis disposed above said table to actuate the roller, glazing tool or brush over the leather on said table in a path substantially parallel to the top of said table with the roller exerting a pressure on said table when moving in one direction and raised above said table to clear the leather when moving in the opposite direction.

The primary object of my invention is to provide a leather rolling, glazing or brushing machine including a mechanical movement of the character described embodying novel and improved features of construction which is strong and durable, simple and inexpensive in construction and operation, and which ensures uniform and thorough rolling, glazing or brushing of leather.

Another object of the invention is to provide a leather rolling, glazing or brushing machine including a mechanical movement of this character comprising a toggle mounted at one end to oscillate on an oscillating eccentric or cam, means for oscillating said toggle on said eccentric, means for swinging the toggle members relatively to each other, and means for coordinating the oscillation of said eccentric and oscillation of said toggle and relative movements of said toggle members so that said free end of said toggle member travels in a substantially straight path.

Further objects are to provide such a machine of the character described including a flat leather supporting table, a shaft having an eccentric thereon operatively connected to said toggle eccentric to oscillate the same, a crank on said shaft operatively connected to one of said toggle members to cause rel-

ative movement of said toggle members and oscillate the toggle on said eccentric so that the free end of said toggle travels in a path parallel to said table, said toggle being adapted to carry a roller, glazing tool or brush to smooth, glaze or brush leather on said table, and to obtain other results and advantages as may be brought out by the following description.

Referring to the accompanying drawings, in which like numerals of reference indicate the same parts throughout the several views,

Figure 1 is a side elevation of a leather rolling, glazing or brushing machine embodying my invention, and showing the toggle in the position at the beginning of its rolling, glazing or brushing stroke;

Figure 2 is a similar view showing the toggle in the position at the end of the rolling, glazing or brushing stroke;

Figure 3 is a top plan view of the machine;

Figure 4 is an elevation of the toggle end thereof, and

Figures 5, 6, 7 and 8 are diagrammatic views showing the relative position of the toggle, toggle members, and its actuating mechanism at various points in the operation thereof.

In the embodiment of my invention shown on the drawings, the reference character 1 designates the drive shaft of the machine which is mounted in suitable bearings 2 on a frame 3, said shaft being driven by any suitable means such as the pulley 4 and belt 5. The frame 3 is provided with a portion 6 which overhangs the leather-supporting table A which is of any suitable and well-known construction including a leather supporting portion 7 yieldingly mounted on springs 8.

A counter shaft 9 is journaled in the portion 6 of the frame transversely of and substantially parallel to the top of the leather supporting portion 7 of the table A, said shaft carrying an eccentric or cam 10 on which is mounted to oscillate a toggle B. The said toggle comprises two members 11 and 12, the first-mentioned having one end journaled on the eccentric 10 and the other end pivotally connected at 13 to one end of the other member 12. The other end of said member 12 is adapted to carry a leather roller 14, glazing tool or brush, of known construction.

It is the purpose of the invention to cause

the roller 14, glazing tool or brush to move over the top of the leather supporting portion of the table A in a substantially straight path substantially parallel to the top of said table, the toggle B causing the roller or glazing tool to exert a pressure on the table when moving in one direction and raising the roller or glazing tool above the table to clear the same when moving in the opposite direction. For the purpose of swinging the toggle B, the member 12 has rigidly connected thereto and at substantially right angles one end of a connecting rod 15, the other end of which is connected to a wrist pin 16 on a crank disk 17 rigidly mounted on the shaft 1. Thus, as the shaft 1 is revolved, the wrist pin 16 is rotated and swings the toggle B about the eccentric 10, and at the same time the wrist pin 16 and connecting rod 15 swing the member 12 of the toggle about its pivot 13 relatively to the member 11 so as to increase the distance between the axis of the eccentric 10 and the roller 14 when the toggle moves in one direction and decrease said distance or break the toggle when the same moves in the other direction. When the distance between the axes of the eccentric 10 and the roller 14 is increased, the toggle causes the roller 14 to exert a pressure on the portion 7 of the table A against the influence of the springs 8, and when the said distance is decreased the roller 14 is lifted above the table to clear the same.

Due to the oscillation of the toggle B about the axis of the eccentric 10, in order to cause the roller 14 to travel in a straight path substantially parallel to the top of the portion 7 of the table and thus exert a uniform pressure thereon, it is necessary to oscillate the eccentric 10 in order to change the relative position of the axis of the eccentric and the axis of the roller 14; and this oscillation of the eccentric must be co-ordinated with the swinging of the toggle B by the connecting rod 15. For this purpose I may provide a crank arm 18 on the shaft 9 and connect said crank arm by a link 19 to an eccentric strap 20 mounted on an eccentric 21 carried by the shaft 1 to rotate therewith. The relative position of the axis of the eccentric 21 and the wrist pin 16 and the adjustment of the eccentric 10 or crank arm 18 on the shaft 9 determines the path of travel of the roller 14.

In the operation of the machine the toggle B, eccentric 10, eccentric 21 and wrist pin 16 are in the positions indicated by Figure 5 at the beginning of the rolling, glazing or brushing stroke of the machine, and the drive shaft 1 rotates in the direction indicated by the arrows. In this position the toggle is broken, that is, the members 11 and 12 are arranged at a relatively sharp angle, and the roller, glazing tool or brush, is

raised above the top of the portion 7 of the table. The leather to be operated upon is placed upon the table beneath the roller 14. Continued rotation of the drive shaft 1 then moves the parts into the position indicated by Figure 6 so as to bring the roller 14 into engagement with the table and cause the same to exert a pressure thereon. This is brought about by the straightening of the toggle by the connecting rod 15. Further rotation of the shaft 1 then swings the toggle B about the eccentric 10. As the toggle B is thus moved the eccentric 21 and link 19 to gradually raise the axis thereof until the roller passes beneath the same, continued movement of the eccentric in the same direction again lowering the axis thereof at the other side of the axis of the shaft 9 after the roller has passed beneath the same. It will thus be seen that the normal path of swing of the roller in an arc about a fixed axis is transformed into a substantially straight path by the varying of the position of the axis. The roller is thus moved to the limit of its rolling stroke as indicated in Figure 7, and further rotation of the shaft 1 then causes through the connecting rod 15 the breaking of the toggle and raising of the roller from the table A as shown in Figure 8. The toggle B is then swung outwardly to the starting position shown in Figure 5, during which movement the eccentric 10 is moved in a direction opposite to that above described to again vary the position of the axis thereof with the roller 14 raised above and clearing the table, after which the operation above described is repeated.

For facilitating the application of the toggle to the eccentric 10, I may form the toggle member 12 in two complementary sections adapted to be applied to the eccentric from opposite sides thereof and secured together by means of bolts 22.

The roller 14 may be substituted by a glazing tool or brush in any suitable manner, but in the present instance I have shown the roller detachably secured to the toggle member 12 by means of plates 23 carrying the roller between them and having one end straight and engaging shoulders 24 on the toggle member, as shown in Figure 4, the said plates being secured to opposite sides of the toggle member by means of a bolt 25. The straight ends of the plates 23 cause the same to move rigidly with the toggle member 12 when the same is actuated by the connecting rod 15. A brush or glazing tool may be secured to the toggle member 12 in the same manner.

While I have shown and described the mechanical movement and a leather rolling, glazing or brushing machine constructed in accordance with my invention embodying

certain details, it will be understood that this is only for the purpose of illustrating the principles of the invention and that many modifications and changes can be made in the detail construction of the device without departing from the spirit or scope of the invention. Therefore, I do not wish to be understood as limiting myself except as required by the following claims when constructed in the light of the prior art.

Having thus described the invention, what I claim is:

1. A machine of the character described including a frame, a movable axis member on said frame, a work supporting table, a toggle comprising two pivotally connected members, one of which is mounted to oscillate on said movable axis member and the other of which is adapted to carry a tool, means for simultaneously oscillating said toggle on said axis member and producing relative movement of said toggle members, and means for moving said axis member simultaneously with the oscillation of said toggle to produce longitudinal movement of the latter and cause the free end thereof to move in straight paths substantially parallel with said table.

2. A machine of the character described including a frame, a work supporting table, an eccentric mounted in said frame for oscillation, a toggle comprising two pivotally connected members, one of which is mounted to oscillate on said eccentric and the other of which is adapted to carry a tool, means for simultaneously oscillating said toggle about said eccentric and producing relative movement of said toggle members, and means for oscillating said eccentric simultaneously with the oscillation of said toggle to produce longitudinal movement of the latter, whereby the free end of said toggle is caused to move in substantially straight paths substantially parallel with said table.

3. A machine of the character described including a frame, a yielding work supporting table, a movable axis member mounted on said frame, a toggle comprising two pivotally connected members, one of which is mounted to oscillate on said axis member over said table and the other of which is adapted to carry a tool for operating on said work, a drive shaft having a crank, a connecting rod rigidly connected to said

second-mentioned toggle member and to said crank to simultaneously oscillate said toggle and move said second-mentioned toggle member on its pivot relatively to the other toggle members, and means for moving said movable axis simultaneously with the oscillation of said toggle to cause longitudinal movement of said toggle, whereby the free end of said toggle is caused to move in substantially straight paths substantially parallel with said table.

4. A machine of the character described including a frame, a yielding work supporting table, a shaft having an eccentric to rotate therewith, a toggle comprising two pivotally connected members, one of which is mounted to oscillate on said eccentric and the other of which is adapted to carry a tool to operate on said work, means for simultaneously oscillating said toggle and producing relative movement of its members, a drive shaft having an eccentric to rotate therewith, and means for connecting said drive shaft to said first-mentioned shaft to oscillate the latter simultaneously with the oscillation of said member, whereby the toggle is moved longitudinally and the free end thereof is caused to move in substantially straight paths substantially parallel with said table.

5. A machine of the character described including a frame, a yielding work supporting table, a shaft having an eccentric to rotate therewith, a toggle comprising two pivotally connected members, one of which is mounted to oscillate on said eccentric and the other of which is adapted to carry a tool to operate on said work, a drive shaft having a crank, a connecting rod rigidly connected to said second-mentioned toggle member and to said crank to oscillate said toggle and move said second-mentioned toggle member on its pivot relatively to the other toggle member, an eccentric on said drive shaft to rotate therewith, and means for connecting said second-mentioned eccentric to said first-mentioned shaft to oscillate the latter simultaneously with the oscillation of said toggle, whereby the toggle is moved longitudinally and the free end thereof is caused to move in substantially straight paths substantially parallel with said table.

ADOLF HINTENACH.
